CURTAIN AND CURTAIN HANGING MEANS

Clive W. Lanphere, New York, N. Y.

Application March 13, 1947, Serial No. 734,376

5 Claims. (Cl. 248—263)

1

This invention relates to improvements in drapery curtains that can be made from any suitable material, and the means for hanging them.

Specifically it relates to a novel type of curtain, and to a new means for hanging them.

One object of the invention is to provide a curtain and valance of integral construction having the appearance of separate construction.

Another object of this invention is to provide this curtain with a valance that is supported at its upper and lower margins in a transverse direction and also at its ends or sides from the transverse portion towards the window.

A further object is to provide means for hanging such a curtain that is simple adding little to the cost of the usual conventional manner of hanging.

These and other objects will be more fully understood by reference to the drawings in which:

Figure 1 is a diagrammatic front view of a pair of curtains for a window.

Figure 2 is a diagrammatic front view of a panel curtain for a window, shown broken away.

Figure 3 is an enlarged cross section broken away at the lower portion, taken on line 3—3, of Figure 1.

Figure 4 is a top view of the curtains shown in Figure 1.

Figure 5 is a front view of a pair of telescopic curtain rods.

Figure 6 is a top view of the rods shown in Figure 5.

Figure 7 is a front view of another pair of telescopic rods.

Figure 8 is a top view of the rods shown in Figure 7.

Figure 9 is a view showing the side of a bracket.

Figure 10 is a front view of the bracket disclosed in Figure 9.

Figure 11 is a front view of another bracket.

Figure 12 is a side view of the bracket shown in Figure 11.

Figure 13 is a diagrammatic design of a panel curtain in the process of construction showing top and side wings.

Figure 14 is a diagrammatic design of a pair of curtains in the process of construction each of said curtains having a wing on one side only.

Figure 15 is a disclosure of the curtain shown in Figure 13 after the wings have been folded, and the curtain hung.

Figure 16 shows the curtains disclosed in Figure 14 after the wings have been folded and the curtains hung.

2

Figure 17 is a side view of an alternative bracket.

Figure 18 is a front view of the bracket shown in Figure 17.

5 While the design or pattern of curtain used is very important in order to secure the desired valance effect, the means for hanging a curtain as disclosed in this invention are essential to contribute to the valance arrangement.

10 Figure 1 discloses a pair of curtains 20 and 21 with a dividing line between them indicated at 23. Reference character 24 identifies a border of curtain 20 that can be so woven or colored or both that it is sharply distinguished from a

15 body portion 25. Character 26 indicates a similar design of the opposite border of curtain 21 this curtain having a body 27. The heads or tops of these curtains are folded over onto the body portions to the points indicated by the lines

20 52 and 53 to form valances 28 and 29 of curtains 20 and 21 respectively.

While the valance portions can be woven and colored to improve their appearance, actual practice shows that a continuation of pattern i. e.

25 longitudinal pattern, produces a rich effect if the border portions are continuous in pattern and likewise the body portions.

Attention is called to the greater degree of color

30 tone at the top corners in Figures 1 and 2. To render a more uniform color a special type of curtain will be described in another part of this description that does not have these heavier color tones at the top corners. Figures 13, 14, 15 and 16 disclose this type of curtain.

35 Figure 2 shows a single panel curtain 30 having distinguished borders 31 and 32 and a top folded valance 33.

The method and means for hanging a curtain will now be described. Figure 9 discloses a side

40 view of a bracket 34. Figure 10 shows a front view. This bracket has a body portion 35 and hooks 42 and 43, extending therefrom. Figure

45 11 discloses a front view of a similar bracket but in reverse position and Figure 12 shows a side view of this bracket. Character 36 identifies it and characters 44 and 45 indicate the hooks, and 37 the body. One design of bracket is sufficient as it is reversible.

50 Bracket 34 can be attached in a perpendicular position to the trim or wall on the left top side of a window by means of nails or screws or any suitable means (means not shown) passing through holes 38 and 39 in this bracket. Bracket 55 36 can be similarly attached to the top right side

of a window by any suitable means passing through holes 49 and 48 in it.

Bracket 34 and bracket 36 have their hooks extending away from each other, the upper hooks holding a rod against a downward pull and the lower hooks securing a rod against an upward pull.

Rods 51 and 51A shown in Figure 5 are placed on hooks 42 and 45 respectively by pressing them downward with the holes 46 and 47 encircling their respective cooperating hooks. Rods 48 and 48A are passed through a rod passageway 49 formed by stitching the lower part of the valance of each curtain to itself transversely as indicated in curtain 21 at 49A and 49B. See Figure 3.

The curtains are then hung by passing the head or top of the curtains with their curtained rods 43 and 48A upward between the window and the rods 51 and 51A and then dropping the valance portions downward in front of the last above mentioned rods with the curtains resting on the top of rods 51 and 51A.

Rods 48 and 48A are then pressed upward with the holes 49 and 50 in these rods respectively encircling hooks 43 and 44 on brackets 34 and 36 respectively. The larger portions of the curtains nearest the window being heavier than the top valances pull these valances upward thus holding the rods 48 and 48A snugly on hooks 43 and 44 respectively.

These suspension means are simple and also prevent shrinkage from laundering interfering with rehanging as the curtains are each held in fixed position by one pair of rods only, i. e. the rods at the lower part of the top valance.

A special design of panel curtain 54 is shown in Figure 13 having side wings 55 and 56 and a top wing 57.

Figure 15 discloses this panel curtain with the wing 55 folded over to line up at the position indicated by line 54A thus forming a valance 54B. This figure also shows wing 56 folded to a position in alignment with the position indicated by line 56A to form a valance 56B, and top wing 57 folded to a position indicated by line 57A to form a valance 57B. These side wings can be sewed at their edges to hold them in place.

Attention is called to the uniformity of valance design as compared to the heavy tone of the corners at the top of Figures 1 and 2. Reference characters 70, 71, 72, 73, 74, and 75 identify dotted lines that indicate where the wings in curtain 54 are sewed to it, after folding. The top wing is held in folded position by rods similar to rods 48 and 48A these rods being at the lower margin of the top valance with this valance hanging from rods similar to rods 51 and 51A (the rods for curtain 54 are not shown).

Figure 14 shows a pair of curtains 61 and 62 having side wings 65 and 66 and top wings 63 and 64 respectively.

Figure 16 discloses wing 65 folded to a position in alignment with the dotted line 65A to form a valance 61B. It shows wing 66 folded to a point indicated by dotted line 66A to form valance 62B. The top wings 63 and 64 are held in folded position at the points indicated by dotted lines 63A and 64A by the rods (rods not shown) in the lower margins of the valances 63B and 64B respectively when these valances hang from the top rods (rods not shown) as do the bodies of the curtains 61 and 62 respectively. Dotted lines 76, 77, 78, 79, 80, 81, 82 and 88 indicate stitching that holds the side wings in folded positions.

Curtains 54, 62, and 61 can have rodways (not shown) similar to that shown in Figure 3.

The bracket disclosed in Figures 17 and 18 has a body 83 and hooks 84 and 85 of integral construction. Reference characters 86 and 87 identify holes in the body for attaching the bracket to the trim of a window or wall, etc.

The novel oppositely positioned hooks shown in this invention not only assure equal distances between the two sets of rods in the valance of the curtain which is important both in appearance and ease of setting the hooks, i. e. bracket, but they also are essential as they hold the rods which in turn hold the top folded wing to form the valance, which affords a curtain and valance of integral construction that have the appearance of separate formation.

The unique folded wings with their two ply structure tend to give the appearance of separate side valances, yet at a very slight addition to the cost of the conventional curtain.

Although a preferred embodiment of this invention is shown and described herein it is understood that modifications may be made therein without departing from the spirit of the invention and the scope of the claims.

What I claim is:

1. A bracket for holding curtain rods, said bracket having a body portion, a hook integral with said body portion, said hook projecting downwardly, and another hook above said first mentioned hook also integral with said body portion, said second mentioned hook projecting upwardly.

2. Bracket means for use with a curtain having a rod passageway therein adjacent to one end of the curtain and a plurality of rods for supporting said curtain comprising; rod holding means disposed on each side of a window to which the assembly is to be attached, said means on each side having a rod holding hook projecting upwardly and another hook projecting downwardly, the hooks on each side being in approximate vertical alignment, the rod held by the lower hooks being disposed in the passageway of the curtain, the curtain extending upwardly from the lower rod and passing over the rod held by the upper hooks and then downward, thus forming a valance in front of the curtain proper.

3. Bracket means for use with a curtain having a rod passageway therein adjacent to one end of the curtain and a plurality of rods for supporting said curtain comprising; two brackets, one for each side of a window to which the assembly is attached, each having a rod holding hook projecting upwardly and another hook projecting downwardly, the hooks on each bracket being in approximate vertical alignment, the rod held by the lower hooks being disposed in the passageway of the curtain, the curtain extending upwardly from the lower rod and passing over the rod held by the upper hooks and then downward, thus forming a valance in front of the curtain proper.

4. A bracket for holding curtain rods having hooks of similar design projecting in opposite directions, one of said hooks projecting upwardly and one of said hooks projecting downwardly, said first mentioned hook being disposed above said second mentioned hook, said hooks being in approximate vertical alignment.

5. A bracket for holding curtain rods, said bracket having a body portion and a pair of hooks of similar design, each of said hooks having a portion extending from said body portion and another portion projecting vertically from said ex-

tending portion, said projecting portion having parallel lateral sides, one of said projecting portions projecting upwardly and another of said projecting portions projecting downwardly, said hooks disposed approximately in vertical alignment.

CLIVE W. LANPHERE.

Certificate of Correction

Patent No. 2,451,034.

October 12, 1948.

CLIVE W. LANPHERE

It is hereby certified that error appears in the printed specification of the above numbered patent requiring correction as follows:

Column 3, line 17, for the word "curtained" read *contained*;
and that the said Letters Patent should be read with this correction therein that the same may conform to the record of the case in the Patent Office.

Signed and sealed this 8th day of February, A. D. 1949.
